CLAIM

[21] Appl. No.: **876,211**

The ornamental design for a hybrid integrated circuit, as shown.

[22] Filed: **Apr. 29, 1992**

DESCRIPTION**Foreign Application Priority Data**

Oct. 30, 1991 [JP] Japan 3-33055
[52] U.S. Cl. **D13/182**
[58] Field of Search 174/52.4, 255, 256, 174/257, 258; 361/380, 384, 392, 395, 397, 399; 364/600, 708; D13/182

FIG. 1 is a top, front and right side perspective view of our new design for a hybrid integrated circuit; FIG. 2 is a front elevational view thereof; FIG. 3 is a rear elevational view thereof; FIG. 4 is a top plan view thereof; FIG. 5 is a bottom plan view thereof; FIG. 6 is a right side elevational view thereof; and, FIG. 7 is a left side elevational view thereof.

FIG. 1
